UNITED STATES PATENT OFFICE.

PHILIP WOOLF, OF NEWARK, NEW JERSEY.

DESIGN FOR A FINGER RING.

Application filed June 17, 1922. Serial No. 2,721. Term of patent 7 years.

To all whom it may concern:

Be it known that I, PHILIP WOOLF, a citizen of the United States, residing at Newark, in the county of Essex and State of New Jersey, have invented a new, original, and ornamental Design for Finger Rings, of which the following is a specification, reference being had to the accompanying drawings, forming a part thereof.

In said drawings, Figure 1 is a top plan view; and Figures 2 and 3 are the two edge views of a finger-ring embodying the fea-

tures of my novel design.

The characters employed to ornament the top of the ring being a Hebrew inscription, which translated into English reads, "God Almighty Bless Thee."

I claim:

The ornamental design for a finger-ring, as shown.

PHILIP WOOLF.
